US00D763502S

(12) **United States Design Patent**
Verleur et al.

(10) **Patent No.:** **US D763,502 S**
(45) **Date of Patent:** **** Aug. 9, 2016**

(54) **CARTOMIZER FOR A VAPORIZER**

(71) Applicant: **VMR Products, LLC**, Miami, FL (US)

(72) Inventors: **Jan Andries Verleur**, Miami Beach, FL (US); **Dan Recio**, Miami, FL (US); **Yifeng Lu**, Miami, FL (US); **Yinjun Zhang**, Miami, FL (US); **Arturo Fajardo**, Miami, FL (US); **Hans Verleur**, El Dorado, CA (US); **Chris Cummings**, Miami, FL (US)

(73) Assignee: **VMR Products LLC**, Miami, FL (US)

(**) Term: **14 Years**

(21) Appl. No.: **29/508,618**

(22) Filed: **Nov. 7, 2014**

Related U.S. Application Data

(63) Continuation-in-part of application No. 14/196,729, filed on Mar. 4, 2014.

(51) **LOC (10) Cl.** **27-02**

(52) **U.S. Cl.**

USPC **D27/167**

(57) **CLAIM**

The ornamental design for a cartomizer for a vaporizer, as shown and described.

DESCRIPTION

FIG. 1 is a bottom perspective view of a cartomizer for a vaporizer;

FIG. 2 is a front view of the cartomizer of FIG. 1;

FIG. 3 is a side view of the cartomizer of FIG. 1;

FIG. 4 is a rear view of the cartomizer of FIG. 1;

FIG. 5 is a bottom view of the cartomizer of FIG. 1; and,

FIG. 6 is a top view of the cartomizer of FIG. 1.

Features shown in broken lines are for illustrative purposes only and form no part of the claimed design.

1 Claim, 1 Drawing Sheet

US D763,502 S
